UNITED STATES PATENT OFFICE

138,129

DESIGN FOR A DRAWING COMPASS

Joseph J. Bruetsch, Detroit, Mich.

Application March 31, 1944, Serial No. 113,095

Term of patent 7 years

(Cl. D52—1)

To all whom it may concern:

Be it known that I, Joseph J. Bruetsch, a citizen of the United States, residing at Detroit, in the county of Wayne and State of Michigan, have invented a new, original, and ornamental Design for a Drawing Compass, of which the following is a specification, reference being had to the accompanying drawing, forming part thereof.

In the drawing:

Fig. 1 is a front elevation of a drawing compass embodying my new design.

Fig. 2 is a side elevation of the compass shown in Fig. 1.

I claim:

The ornamental design for a drawing compass, substantially as shown.

JOSEPH J. BRUETSCH.
